His Attorney.

UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

STATIONARY INDUCTION APPARATUS.

1,282,086.

Specification of Letters Patent.

Patented Oct. 22, 1918.

Application filed May 2, 1917. Serial No. 166,023.

To all whom it may concern:

Be it known that I, SVEND E. JOHANNESEN, a citizen of the United States, residing at Pittsfield, county of Berkshire, State of Massachusetts, have invented new and useful Improvements in Stationary Induction Apparatus, of which the following is a specification.

My invention relates to various kinds of stationary induction apparatus, such as transformers, auto-transformers, some rectancies, etc.; for the purpose of simplicity, however, I shall hereafter refer substantially only to "transformers," intending to include under that term all such related stationary induction apparatus. My invention relates particularly to transformers of the so-called distributed core type. An object of my invention is to provide an improved core.

Cores of transformers of the distributed core type are made up generally of a number of separate parts or units distributed substantially equiangularly about the legs carrying the windings, each core part or section providing a leg which joins with other legs of other core parts to form a leg for a winding. My invention is directed principally toward improving the construction of the center or winding leg.

It is understood to be desirable that the space occupied by the core material of a winding leg should be of as great cross area as possible for a given perimeter; the degree of economy of material required for a transformer depends to a considerable extent upon the relation between the perimeter of the core leg to be encircled by a winding to the cross area of the space within the winding occupied by the material of the core. It is desirable therefore that the cross section of a winding leg approach as nearly as possible a circle, since a circle has the greatest area for a given perimeter. Furthermore a winding leg of a circular cross section, or a cross section approaching a circle, is preferable to one in which the cross section greatly departs from a circle since a conductor surrounding a circular leg is subjected to the least bending, and bending on the longest possible radii, and hence suffers the minimum injury to its insulation by reason of the bending.

A further requirement is that the core be composed of as few different sizes of

laminations as possible. If more than a few sizes of laminations are required, the device is more difficult and expensive to manufacture, especially in the smaller sizes. By my invention it is possible to provide a core in which the winding leg is a many-sided polygon in cross section, approaching a circle, and which comprises but a very few different sizes of laminations. Furthermore my invention is subject to many modifications which adapt it to meet the varied requirements of transformer manufacture, and has numerous other advantages appearing from a fuller consideration of the invention and commanding my invention to general use.

Preferably the core is made up of three parts or units spaced substantially 120° apart about the center or winding leg, for my invention is most applicable to such a number of core units. Such a number of core units also provides considerable space between the core units for bringing out the necessary leads, taps and cross connections of the windings and necessitates less insulation thereof than were more core units employed.

In the accompanying drawings I have illustrated and hereinafter I have described the best forms of my invention and certain of the best modifications thereof that I now know of; the principles of my invention will be understood therefrom.

Figure 1 is a perspective view of a three part or three unit distributed core type transformer embodying my invention. Fig. 2 is a plan view, partly in section, of the core of the transformer of Fig. 1. Figs. 3 and 4 are plan views, partly in section, of modifications thereof. Fig. 5 is a plan view, partly in section, illustrating the winding leg of the transformer of Fig. 2 modified to increase the size of the axial passage. Fig. 6 is a plan view, also partly in section, of a modification of the winding leg of Fig. 2 wherein the axial passage is partially closed. Figs. 7, 8 and 9 are plan views, also partly in section, showing further modifications of the core of Fig. 2. In Fig. 1 is illustrated probably the most generally suitable form of the invention I now know of. The three parts or units 21, 22 and 23 of the core, it will be observed, are placed substantially equiangularly, in this case 120° apart, about the common inner core leg 25 and the axis

thereof. Each part or unit of the complete core comprises an inner leg 10, an outer leg 11 and two yokes 12 joining the ends of the inner and outer legs. This structure provides a window or space 13 within the core unit in which is disposed the winding 15 of the device. Each core part or unit is laminated, and may be made up of L-shaped laminations as indicated and as has heretofore been common in this general type of core. The three parts or units of the transformer of Fig. 1 are similar and the inner legs of the three units join and intermesh, as appears from the drawing, to form the inner core leg 25 which is surrounded by the winding 15. The details of my invention will be better understood from a consideration of the remaining figures.

Each core part or unit of the transformer of Fig. 1 (see Fig. 2) consists of three layers of laminations 26, 27 and 28 which are indicated on the part 23 of Fig. 2 by the lines 29 and 30 separating these layers. The layer 27 may be further regarded as consisting of two parts 32 and 33, indicated on this core part or unit 23 by the dividing line 34. The outer leg 11 of each core part of this particular transformer is "fanned", that is, is provided with more laminations or thicker laminations than are contained in the inner leg in order that the outer leg may be operated at some lower magnetic density than the inner leg. The inner leg portion of the two part layer 27 of each core part 35 is made up of laminations of a uniform width, the width indicated by the length of the line 37. The part 33 of each such layer joins at its edges the other two parts 33 of the other two units at their opposite edges, thus forming the triangle 38 which is the cross section of the axial passage through the core leg. This space or passage 38 may be occupied by a bolt attaching the core clamping plates, or may be used solely 45 as a ventilating passage for the core or otherwise, or may be closed in any manner.

It will be observed that this triangular passage 38 is formed by reason of the facts that the laminations of each part 33 are of uniform width within the core leg and that all the laminations of each part-layer 33 terminate in a single plane which is perpendicular to the planes of the laminations of the part-layer 33. The parts 32 of the layers 27 lie at one and the same side of their respectively adjacent parts 33. The laminations of each of the part-layers 32 within the core leg likewise terminate in a single plane, but this plane, unlike the terminal plane of the laminations of the part-layer 33, is substantially parallel to the planes of the laminations of the part 33 of the layer 27 of the respectively adjacent core part or unit; in fact the laminations 65 of each part-layer 32 terminate on one side

of the respectively adjacent core part or unit—that is, in the construction illustrated the laminations of the part-layer 32 of each of the two-part layers 27 terminate, or abut, against the laminations of the part-layer 33 of the similar two-part layer 27 of an adjacent core unit. Since the inner-leg laminations of the two part-layers 32 and 33 are of uniform width and terminate in two planes, the edges of these leg laminations 75 toward the window of their respective core part likewise lie in two planes, and it will be observed that these planes (by reason of the construction previously described) intersect in the outer surface, or the window 80 surface, of the core leg. The layer 28 of each core part lies against the side of the layer-part 33 (of the same core part or unit) which is opposite the layer-part 32. The inner-leg laminations of the part 28 are 85 of uniform width and narrower than the inner-leg laminations of the layer 27 as will be observed from the drawing, and terminate on the side of the adjacent core part and likewise on one side of the layer-part 90 32 of the respectively adjacent core part. The layer 26 lies against the side of layer 27 opposite the layer 28. The inner-leg laminations of the layer 26 are likewise narrower than the inner-leg laminations of 95 the layer 27 and also are of uniform width; the widths of the inner-leg laminations of the layer 26 may be greater or less than, or equal to, the widths of the inner-leg laminations of the layer 28 depending upon the 100 thicknesses (numbers of laminations) in the different layers 28, and other considerations. Preferably, however, the widths of the inner-leg laminations of the layer 26 are such that these laminations terminate toward the 105 window of their respective core part (when their opposite edges terminate on the side of the adjacent core part) in the same plane as the window edges of the inner-leg laminations of the layer part 32. Also the widths 110 of the inner-leg laminations of the layer 28 are preferably such and the thicknesses of the layers 26 (that is the numbers of laminations used in said layers 26) are such that the plane of the window edges of the laminations of each of the layers 28 is the plane 115 of the adjacent side of the inner-leg portion of the respectively adjacent layer 26. Preferably also these planes intersect the planes of the window edges of the inner-leg laminations of the layer-parts 33 in the outer (or window) surface of the core leg as appears from the drawing. This consideration, it will be observed, provides a transformer core in which the center leg, which carries the winding, has for its cross section a nine sided figure. The windings may closely follow the surfaces of the winding legs or may depart somewhat from such surfaces, for example to provide ventilating 120 125 130

passages. If desirable, as to provide cooling ducts for the windings or otherwise, a part of all of each layer 26 may be omitted; this idea is illustrated and described in 5 more detail hereinafter. It will be observed that a transformer core of the construction thus described may be constructed with relations between the widths of the laminations of the leg and the thicknesses of the 10 layers (and part layers) of the laminations, materially different from those shown in the drawing without however departing from the nine sided cross section of the center leg. It is possible, therefore, to change the regularity of the nine sided cross section and to 15 change the equalities of the lengths of the sides of the nine sided figure. Such departures, however, may involve increasing the number of sizes (widths) of laminations 20 required for the inner leg of each core part. It will probably be generally found preferable to so proportion the different layers that only two widths (or sizes) of inner leg laminations will be required, one size or 25 width being used for the layers 26 and 28, the other size being used for the layer 27. Substantially such a relation is illustrated in Fig. 2.

It will be observed that due to the passage 30 38, the cross area within the perimeter of the core leg is greater than the cross area of the material of the core leg. The magnetic flux carrying power of the core leg depends substantially entirely, of course, on the cross 35 area of the material of the core leg, and therefore the flux carrying power of the core leg 25 is reduced, as it were, by reason of the presence of the passage 38 and this passage represents so much waste space unless this 40 passage is used for some useful purpose as before indicated. However, even though this passage is used for no useful purpose whatsoever, the construction before described possesses such advantages over the prior art as 45 to more than outweigh the loss of this space in a great number of cases, and where this passage threatens to assume such proportions as to nullify the advantages of the construction, as in some of the larger sizes of 50 the apparatus, the passage may be more or less filled with active material as hereinafter described in some detail, and its detrimental effects correspondingly reduced.

Fig. 3 illustrates a modification of the core 55 of Fig. 2 in which the layers 26 are omitted and the layers 28 built out (increased in thickness) to replace the material of the omitted layers 26. It will be observed that the layers 28 are of such thickness (numbers 60 of laminations) that the exposed sides of the layers 28 lie in the same planes as the window edges of the part-layers 32 of the respectively adjacent core parts or units.

Fig. 4 illustrates a further modification; 65 more accurately it is a modification of the

core of Fig. 3, although obviously the case of Fig. 2 may be similarly modified. In the core of this figure the laminations of the part-layers 33 (of the layers 27) have been, as it were, moved inwardly uniformly so as 70 to entirely close the triangular opening 38 of Figs. 2 and 3. This provides a space 41 in each core part or unit which may be used for ventilation if desired.

Fig. 5 illustrates another modification in 75 which the laminations of the part-layers 33 are uniformly moved outwardly to transform the triangular core passage into a hexagonal passage 52. The dotted triangle within the opening 52 illustrates the passage as 80 it would be had not the laminations of the part-layers 33 been moved outwardly. The dotted lines 54 likewise illustrate the terminations of the window edges of the inner leg laminations of the part-layers 33 as they 85 would be had not these laminations been moved outwardly. In this figure, however, the laminations of the part-layers 33 are shown so displaced outwardly that a part of them terminate toward their core windows 90 in the same planes as the laminations of the respectively adjacent part-layers 32, the remainder of the laminations of the part-layers 33 terminating in the planes of the laminations of the layers 28. The nine sided 95 cross section for the winding leg of the core has been departed from, and this cross section has become a six sided figure. However, in compensation therefor the axial opening in the core leg is of larger size, 100 which adapts this particular modification to the smallest sizes in which the triangular shaped opening would not be sufficient size, for example, to admit the bolt necessary to 105 secure the clamping plates together.

The core of Fig. 6 is particularly adapted for the large sizes of transformers in which the triangular shaped passage through the core leg becomes of such size as to unduly lower the efficiency of the apparatus; this 110 form may, however, be used in any case where a single fairly large passage through the core leg is unnecessary. It will be observed that the core leg of this construction differs from that of Fig. 2 particularly in 115 the use of laminations of two widths in the layer 27. The laminations at the two sides of the layer 27 in Fig. 6 (as well as in Fig. 2) are of a single uniform width. Contained between these side laminations of the layer 120 27 (in Fig. 6) are other laminations, indicated generally by 61, of greater (and also uniform) width. The window edges of 125 these laminations 61 terminate in the same planes as the window edges of the remainder of the laminations of the part-layers 33. These laminations 61 consequently extend nearer the center of the core leg than the other laminations. The extension toward the core center, of these laminations 61 of 130

each core part assumes a generally rectangular form, and at the maximum (as indicated in the drawing) each extension engages a similar extension of another core part and 5 likewise the inner face of a part-layer 33 other than its own. The maximum of the extension of the laminations 61 (if the remainder of the construction is to remain unchanged) is such that the side edges of the 10 part-layers 33 continue to engage opposite side edges of the adjacent part-layers 33 at the apexes of a substantially equilateral triangle as in this and all the preceding figures. By this means the otherwise single axial passage 15 is to a large extent utilized by active magnetic material of the core.

The core of Fig. 7 differs from those preceding, particularly in that it requires four widths or sizes of laminations for the inner 20 core leg and in that the three parts or units are not similar to each other. The part 71 comprises, like the cores of Figs. 2 and 6, the layer 27, the layer 26 and the layer 28, and further a layer 72. The inner leg laminations 25 of the layer 72 are, as appears from the drawing, much narrower than any of the other laminations in the core part 71. The core part 73 comprises also the layers 26, 27 and 28, but the layer 27 is made up of three 30 part-layers instead of two. A part-layer, like 32 of Fig. 2, appears at each side of the part-layer similar to the part layer 33 of Fig. 2. The laminations of the layer 28 of core part 73 are considerably narrower than 35 the laminations in the layer 26 in this core part 73, and in fact this layer 28 of narrower laminations more nearly resembles the layer 72 of the core part 71 of the present figure. In core part 75 the layer 27 comprises only 40 a part-layer like 33 of Fig. 2; the layers 26 and 28 lie directly against this layer 27 as in Fig. 2. A layer 72, like layer 72 of core part 71, lies against layer 28 and terminates on the side of the adjacent core part 71. The 45 respective core units are provided with extensions toward the center of the core leg similar to the extensions of the laminations 61 of Fig. 6. It will be observed that certain laminations of layer 72 have been omitted, 50 thereby providing ventilating spaces for the coils. This omission of laminations for this purpose was indicated as possible during the description of Fig. 2.

Fig. 8 is as to its inner core leg a modification of the core of Fig. 3 made along the same lines as the core of Fig. 2 (or perhaps better of Fig. 6) was modified to produce the core of Fig. 7; the core parts or units are dissimilar as to these inner legs. The extra 55 narrow laminations of the layers 72 of Fig. 7 do not, however, appear in the core of Fig. 8 as illustrated. This core further distinguishes from anything shown before in that the narrow inner-leg laminations of the 60 different core parts or units have corre-

spondingly narrow outer legs, and the wider inner-leg laminations having correspondingly wide outer legs.

Fig. 9 illustrates perhaps more clearly than any of the earlier figures the result of 70 omitting some of the laminations from the exposed sides of the core parts. This figure illustrates the core of Fig. 3 with some of the narrower inner-leg laminations (and the corresponding yoke and outer-leg laminations) omitted, the winding of the apparatus being shown. As clearly appears, there are three ventilating or cooling passages 91 provided for cooling the interior of the winding. This omission of laminations also re- 75 duces the perimeter which it is necessary for the winding to surround and hence reduces the mean length of turn. The reduction in perimeter obtained by omitting certain of the laminations may in some cases be 80 desirable for other reasons than that of cooling the windings.

While I have described the principle of my invention and the best mode I have contemplated for applying this principle, other 90 modifications will occur to those skilled in this art and I aim in the appended claims to cover all modifications which do not involve a departure from the spirit and scope of my invention. It will be understood that 95 by the use of the term "transformer" in the following claims I do not limit my invention to a particular type of apparatus, but that my invention is applicable to various kinds of stationary induction apparatus as before 100 indicated.

What I claim as new and desire to secure by Letters Patent of the United States, is,—

1. A transformer core comprising a plurality of angularly spaced parts or units, 105 each having a window to receive the transformer winding, the respective inner legs of the parts or units being joined to form a leg of the core, the inner leg of each of said core parts or units comprising a layer of laminations in which laminations of a uniform width are disposed at both sides of a plane passing through the axis of said core leg and terminate in the outer surface of said core leg in a plurality of planes, and a layer of 110 narrower laminations of uniform width lying against one side of the first mentioned layer and abutting at their inner edges against a side of an adjacent core part, said narrower laminations terminating in the 115 outer surface of said core leg in another plane.

2. A transformer core comprising a plurality of angularly spaced parts or units, 120 each having a window to receive the transformer winding, the respective inner legs of the parts or units being joined to form a leg of the core, the inner leg of each of said core parts or units comprising a layer of laminations in which laminations of a uni- 125

form width are disposed at both sides of a plane passing through the axis of said core leg and terminating in the outer surface of said core leg in a plurality of planes, and 5 two layers of narrower laminations lying at the opposite sides of the first mentioned layer, each of said two layers being of laminations of uniform width, the laminations of one of said layers terminating in the outer 10 surface of said core leg in another plane.

3. A transformer core comprising a plurality of angularly spaced parts or units, each having a window to receive the transformer winding, the respective inner legs 15 of the core parts or units being joined to form a leg of the core, the inner leg of each of said core parts or units comprising a layer of laminations in which laminations of a uniform width are disposed at both sides of a plane passing through the axis of said core leg, said laminations being also disposed at both sides of other laminations extending nearer the center of said core leg, the laminations of said layer terminating in the 20 outer surface of said core leg in a plurality of planes, and a layer of narrower laminations of uniform width lying at one side of the first mentioned layer, said narrower laminations terminating in the outer 25 surface of said core leg in another plane.

4. A transformer core comprising three parts or units, each having a window to receive the transformer winding, the respective inner legs of the three parts or units being 30 joined to form a leg of the core and said core parts or units being spaced apart substantially 120° about said core leg, the inner leg of each of said core parts or units comprising a layer of laminations in which laminations of a uniform width are disposed at both sides of a plane passing through the axis of said core leg and terminate in the outer surface of said core leg in two planes, and a layer of narrower laminations of uniform width lying against one side of the first 40 mentioned layer and abutting at their inner edges against a side of an adjacent core part, said narrower laminations terminating in the outer surface of said core leg in a third 45 plane.

5. A transformer core comprising three parts or units, each having a window to receive the transformer winding, the respective inner legs of the three parts or units being 50 joined to form a leg of the core and said core parts or units being spaced apart substantially 120° about said core leg, the inner leg of each of said core parts or units comprising a layer of laminations in which laminations of a uniform width are disposed at both sides of a plane passing through the axis of said core leg and terminate in the outer surface of said core leg in two planes which intersect in said surface, and two 55 layers of narrower laminations, each of said

two layers being of laminations of uniform width, lying at the opposite sides of the first mentioned layer and each of said two layers abutting at its inner edge against a side of the respectively adjacent core part, the laminations of one of said two layers terminating in the outer surface of said core leg in a third plate intersecting one of said planes in said surface. 70

6. A transformer core comprising a plurality of angularly spaced parts or units, each having a window to receive the transformer winding, the respective inner legs of the core parts or units being joined to form a leg of the core, the inner leg of each of said core parts or units comprising laminations near the core part center, the edges of which at the outer surface of said core leg lie in a single plane, and also comprising other laminations lying at the opposite sides 85 of the first mentioned laminations, the outer edges of which lie in two other planes which intersect the first mentioned plane in the outer surface of said core leg. 80

7. A transformer core comprising a plurality of angularly spaced parts or units, each having a window to receive the transformer winding, the respective inner legs of the core parts or units being joined to form a leg of the core, the inner leg of each of said 90 core parts or units comprising laminations near the core part center, the edges of which at the outer surface of said core leg lie in a single plane, said plane being at an angle to the planes of the laminations of the two adjacent core parts or units, and also comprising other laminations at the two sides of said layer, the outer edges of which at each side of said layer lie in a plane which intersects the first mentioned plane in the outer 95 surface of said core leg and which is generally parallel to the plane of the laminations of the respectively adjacent core part or unit. 100

8. A transformer core comprising a plurality of angularly spaced parts or units, each having a window to receive the transformer winding, the respective inner legs of the parts or units being joined to form a leg of the core, the inner leg of each of said core parts or units comprising laminations at 115 each side thereof the edges of which at the outer surface of said core leg lie in a plane generally parallel to the plane of the laminations of the respectively adjacent core part or unit, each core part or unit also comprising other laminations between said laminations at the two sides of the core part or unit which extend nearer the center of said core leg than the first mentioned laminations and the edges of which in the surface of said 120 core leg lie in another plane intersecting the first mentioned planes in the surface of said core leg. 125

9. A transformer core comprising three parts or units, each having a window to re- 130

ceive the transformer winding, the respective inner legs of the parts or units being joined to form a leg of the core and said core parts or units being substantially equi-
 5 angularly spaced about the said core leg, the inner leg of each core part or unit comprising laminations at both sides thereof the edges of which at the outer surface of said core leg lie in two planes at an angle of sub-
 10 stantially 120° to each other, each core part or unit also comprising other laminations between said laminations at the two sides of the core part or unit which extend nearer the center of said core leg than the first men-
 15 tioned laminations, the outer edges of which lie in another plane which intersects the first mentioned planes in the surface of said core leg.

10. A transformer core comprising a plu-
 20 rality of angularly spaced parts or units, each having a window to receive the trans-
 former winding, the respective inner legs of the parts or units being joined to form a leg of the core, the inner leg of each of
 25 said core parts or units comprising a two-
 part layer of laminations of uniform width, the inner side edges of one part of said layer engaging opposite side edges of similar part
 30 layers of the two adjacent core parts or
 35 units, the other part of said layer abutting
 40 against one side of one of said adjacent core
 45 parts, and also comprising a layer of nar-
 50 rower laminations of uniform width lying
 against said first mentioned layer.

5. 11. A transformer core comprising a plu-
 rality of angularly spaced parts or units, each having a window to receive the trans-
 40 former winding, the respective inner legs of the parts or units being joined to form a leg
 45 of the core, the inner leg of each of said core
 50 parts or units comprising a two-part layer
 of laminations in which the laminations at the two sides of the layer are of uni-
 form width, the inner side edges of one part
 55 of said layer engaging opposite side edges of
 60 similar part-layers of the two adjacent core
 65 parts or units, the other part of said layer
 abutting against one side of one of said ad-
 jacent core parts, and also comprising a layer
 50 of narrower laminations of uniform width
 lying against said first mentioned layer.

12. A transformer core comprising three
 parts or units, each having a window to re-
 ceive the transformer winding, the respective
 55 inner legs of the parts or units being joined
 to form a leg of the core and said core parts
 or units being spaced apart substantially
 60 120° about said core leg, the inner leg of
 65 each of said core parts or units comprising
 a two-part layer of laminations in which
 the laminations at the two sides of the layer
 are of uniform width, the inner side edges
 70 of one part of said layer engaging opposite
 side edges of similar part-layers of the other
 two core parts or units at the apexes of a

substantially equilateral triangle, the other
 part of said layer abutting against a side of
 the adjacent core part or unit, and also com-
 75 prising a layer of narrower laminations of
 uniform width lying against said first men-
 tioned layer and abutting against a side of
 the adjacent core part.

13. A transformer core comprising three
 parts or units, each having a window to re-
 ceive the transformer winding, the respec-
 75 tive inner edges of the parts or units being
 joined to form a leg of the core and said
 core parts or units being spaced apart sub-
 stantially 120° about said core leg, the inner
 80 leg of each of said core parts or units com-
 prising a two part layer of laminations in
 which the laminations at the two sides of
 the layer are of uniform width, the inner
 85 side edges of one part of said layer engag-
 ing opposite side edges of similar part
 layers of similar layers of the other two core
 90 parts or units at the apexes of a substantially
 equilateral triangle and some of the lamina-
 tions of said layer extending within the out-
 95 lines of said triangles, the other part of
 said layer abutting against one side of the
 adjacent core part or unit, and also compris-
 100 ing a layer of narrower laminations of uni-
 form width lying against said first men-
 tioned layer and abutting against one side
 105 of the adjacent core part.

14. A transformer core comprising a plu-
 rality of angularly spaced parts or units,
 each having a window to receive the trans-
 100 former winding, the respective inner legs of
 the parts or units being joined to form a leg
 of the core, the inner leg of each of said core
 105 parts or units comprising a two part layer
 of laminations in which the laminations at
 the two sides of the layer are of uniform
 110 width, the edges of said laminations in the
 outer surface of said leg of the core lying in
 two planes which intersect in said surface,
 and a layer of narrower laminations lying
 115 at one side of the core part or unit, the edges
 of said narrow laminations in the outer sur-
 face of said leg of the core lying in a third
 plane.

15. A transformer core comprising a plu-
 rality of angularly spaced parts or units,
 each having a window for receiving the
 transformer winding, the respective inner
 115 legs of the parts or units being joined to
 form a leg of the core, the inner leg of each
 of said core parts or units comprising a two
 120 part layer of laminations in which the lam-
 inations at the two sides of the layer are of
 uniform width and in which other lamina-
 tions between said laminations of uniform
 125 width extend nearer the center of said leg,
 the edges of said laminations in the outer
 surface of said leg of the core lying in
 planes which intersect in said surface, and
 a layer of narrower laminations lying at
 130 one side of the core part or unit, the edges

of said narrower laminations in the outer surface of the said leg of the core lying in another plane.

16. A laminated core part or unit for a distributed core for electrical apparatus having an outer leg, an inner leg, and yokes joining the ends of said legs, said inner leg comprising a two part layer of laminations in which the laminations at each of the two sides of the layer are of uniform width, the edges of said laminations toward the window of said core part or unit lying in planes which intersect in the surface of said inner leg, and a layer of narrow laminations lying against said first mentioned layer.

17. A laminated core part or unit for a distributed core for electrical apparatus

having an outer leg, an inner leg, and yokes joining the ends of said legs, said inner leg comprising layers of laminations the edges 20 of which toward the window of said core part or unit lie in a plurality of planes which intersect each other in the window surface of said inner leg, one of said planes being at right angles to the planes of said 25 laminations, there being one plane substantially at right angles to the planes of the laminations of said core part or unit and a plane at each side thereof at another angle to the planes of said lamination. 30

In witness whereof I have hereunto set my hand this 27th day of April, 1917.

SVEND E. JOHANNESEN.

Correction in Letters Patent No. 1,282,086.

It is hereby certified that in Letters Patent No. 1,282,086, granted October 22, 1918, upon the application of Svend E. Johannesen, of Pittsfield, Massachusetts, for an improvement in "Stationary Induction Apparatus," an error appears in the printed specification requiring correction as follows: Page 5, line 73, for the word "plate" read *plane*; and that the said Letters Patent should be read with this correction therein that the same may conform to the record of the case in the Patent Office.

Signed and sealed this 10th day of December, A. D., 1918.

[SEAL.]

Cl. 175—356.

F. W. H. CLAY,

Acting Commissioner of Patents.
